UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,208,836.

Specification of Letters Patent. Patented Dec. 19, 1916.

Application filed June 22, 1914. Serial No. 846,590.

To all whom it may concern:

Be it known that I, WILLIAM J. ROCHE, a resident of Meadville, in the county of Crawford and State of Pennsylvania, have invented a new and useful Improvement in Garment-Stays, of which the following is a specification.

This invention relates to garment stays and particularly to wire corset stays.

10 The object of the invention is to provide a flexible wire garment stay which yields readily in all directions, in which the bending strains are distributed over a considerable length of wire, so as to avoid crystallization and deterioration of the metal and prevent the stay from taking a permanent set, and to provide a corset stay which is stronger and more resilient than prior stays and offers more resistance to bending strains, 20 particularly in the edgewise direction.

The invention comprises the stay herein-after described and claimed.

In the drawings, Figure 1 represents a face view of a stay embodying the invention; 25 Fig. 2 is an edge view thereof; Fig. 3 is a face view of a modified form of stay; and Figs. 4, 5 and 6 are face views of other modifications, the wire in Fig. 5 being shown as a single line for simplification.

30 The stay shown in the drawings is formed from wire, a single continuous wire 1 being shown, which is bent back and forth in sinuous form to form a series of oppositely disposed main loops or eyes 2 lying along the edges of the stay and which are connected by transverse intermediate portions or crossings 3. Generally speaking the intermediate crossings are alternately inclined in opposite directions so that the main loops or eyes 2 35 are progressively arranged in staggered relation longitudinally of the stay, although this is not essential. Said eyes or loops may all lie in substantially the same flat plane or may overlap each other slightly longitudinally of the stay as shown at 4, Fig. 3. Said eyes or loops have broad closed outer ends and are open at their inner ends, and the wire of the broad outer ends of the main loops or eyes is bent or coiled into a complete 45 turn, to produce a series of smaller loops or eyes 5, each of which lies wholly within one of the main eyes or loops 2. Said smaller eyes 5 may be of any suitable size, but preferably are slightly smaller than the 50 main eyes or loops so that the wire is not

tightly coiled at the edges of the stay and lies within the large main eye and thereby increases the amount of wire in the stay and its resiliency, but without materially increasing its thickness or making it bulky. 60

The intermediate portions or crossings 3 may be substantially straight, as shown in Figs. 1 and 3, or may be bent or deflected intermediate the edges of the stay. For example, each crossing portion of the wire in 65 Fig. 4 is bent toward one end of the stay to form a trapezoidal loop 6 which increases the total amount of wire in the stay but especially the effective length of the crossing portions subjected to torsional strains when 70 the stay is bent flatwise.

In Fig. 5 the crossing portions of the wire are bent intermediate the edges of the stay into sinuous or S-shaped form, as shown at 75, which produces a plurality of small loops 75 or folds in the wire, the loops or folds in the successive crossings lying in a row along the middle of the stay.

In Fig. 6 each crossing portion of the wire is bent or coiled intermediate its edges to 80 form a small loop, eye or convolution 8.

In each of the forms shown the length of the crossing portions of the wire and also of the eyes or loops is increased, which enables the stay to better resist bending strains 85 and distribute said strains over a greater length of the wire and consequently avoids crystallization and breakage. The stay may also be readily constructed as there are no tight coils. 90

What I claim is:

1. A garment stay, comprising wire bent to form a series of main loops or eyes lying at the edges of the stay and connected by transverse portions or crossings, said eyes or 95 loops having broad outer ends the wire of which is coiled to form a closed loop or eye smaller than the main loop or eye and extending toward the center line of the stay, each of said closed loops or eyes lying wholly 100 within one of the main loops or eyes along the edges of the stay.

2. A garment stay, comprising wire bent to form a series of main loops or eyes lying along the edges of the stay and connected 105 by transverse portions or crossings, said main loops or eyes having broad outer ends the wire of which is bent or coiled to form closed convolutions smaller than and lying within said main eyes or loops. 110

3. A garment stay, comprising wire bent back and forth to form a series of main loops or eyes lying along the edges of the stay and connected by transverse portions or 5 crossings, said main loops or eyes having broad outer ends the wire of which is bent or coiled to form closed convolutions smaller than and lying within said main eyes or loops, the crossing portions of the wire being

bent intermediate the edges of the stay to 10 form a series of closed loops or convolutions lying along the center line of the stay.

In testimony whereof, I have hereunto set my hand.

WILLIAM J. ROCHE.
